UNITED STATES PATENT OFFICE.

FRANK J. BEIER, OF CHICAGO, ILLINOIS, ASSIGNOR OF TWO-THIRDS TO BERNARD S. AUSTRIAN AND CHARLES S. ROSENTHAL, OF CHICAGO, ILLINOIS.

VENDING-MACHINE.

SPECIFICATION forming part of Letters Patent No. 761,351, dated May 31, 1904.

Application filed August 22, 1902. Serial No. 120,650. (No model.)

To all whom it may concern:

Be it known that I, FRANK J. BEIER, of Chicago, in the county of Cook and State of Illinois, have invented certain new and useful Improvements in Vending - Machines; and I do hereby declare that the following is a full, clear, and exact description thereof, reference being had to the accompanying drawings, and to the letters of reference marked thereon, which form a part of this specification.

This invention relates to an improvement in vending-machines of that class usually actuated by a coin-controlled mechanism.

The invention as herein shown is applied to a cigar-vending machine; but it will be obvious from the following description that certain of the features thereof may be applied to machines for vending other articles of merchandise.

The invention consists of the matters herein-after set forth, and more particularly pointed out in the appended claims.

In the drawings, Figure 1 is a transverse vertical section of a vending-machine embodying the improvements constituting my invention. Fig. 1^a is a sectional detail taken on line 1^a 1^a of Fig. 1. Fig. 2 is a front elevation of the principal parts of the mechanism for releasing the articles of merchandise one by one from the machine. Fig. 3 is a rear perspective view of the parts of the machine shown in Fig. 2. Fig. 4 is a diagrammatic plan view of the releasing-belt cut and stretched flat.

As shown in the drawings, the casing containing the vending mechanism and the merchandise consists of a lower or base portion A, within which the principal parts of the vending mechanism is contained, and an upper portion A', the latter of which contains the package from which the merchandise is to be vended—as, for instance, the cigar-box B. (Shown in Fig. 1.) The front and rear walls a a', respectively, of the upper section A' of the case are made of glass, and said upper section of the case is made of a size to receive a cigar-box with the lid thrown backwardly, as shown in Fig. 1, whereby the cigars and the label are displayed through the front trans-

parent wall in the same manner as cigars are displayed in a selling-case. Moreover, by reason of the transparent rear wall a', the revenue-stamps and factory notices on the box are also displayed. The front wall a of the upper section of the casing, consisting principally of glass, as aforesaid, is preferably hinged at one side to the end wall from the upper section, the hinges being shown at a². The cigar-box B is adapted to be inserted into the upper section A' from the front thereof when the swinging wall or door a is open.

The box B is provided inside thereof with racks for the cigars contained therein, and said racks are so disposed as to maintain the cigars in upright positions in the box and to separate the same from each other, so that the discharge of a cigar from the box does not affect the position of the cigars which remain therein. In Figs. 1 and 2 the box is shown as provided with a lower rack B', consisting of longitudinal and transverse strips b b', respectively, which intersect to form a plurality of rectangular pockets, which are occupied by the lower ends of the cigars. The strips from which the rack B' is made may be of sufficient width to hold the cigars in vertical positions; but I prefer to use in connection with a narrow rack B' a supplemental rack B² at the upper side of the box. Said supplemental rack, as herein shown, consists of a horizontal piece of cardboard or like material provided with a plurality of openings, which are located vertically over and register with the pockets of the lower rack and which are adapted to receive the upper ends of the cigars. The lower wall of the box B is removed from the box after the latter has been inserted into the upper section of the case in the manner shown in Fig. 1, so at this time the lower ends of the cigars rest on the part of the vending mechanism, which is constructed to release the cigars one at a time in a manner to be hereinafter described. In Fig. 2 the end walls of the box are shown as provided at their lower inner margins with inwardly-opening grooves b², from which the lower side or wall of the box has been removed.

The mechanism for releasing the cigars one at a time from the box B consists generally of an endless belt or band C, the upper lap of which is horizontal and parallel with the lower part of the cigar-box and constitutes when the lower wall of the box is removed a support for the cigars, said cigars resting on end on said band or belt, as indicated in Fig. 2. Said releasing band or belt is endless and is trained about horizontal rollers $c c' c^2 c^3$, mounted in a suitable frame which is located in the lower section of the casing. Said frame embraces a horizontal base D, which rests on the bottom wall of the lower section of the casing. Rising from said base D are four corner posts or standards D', and the upper ends of the standards of each pair at the ends of the base-board are connected by a transverse member D². The connected pair of posts D' at the opposite ends of the frame are connected by longitudinal frame members D³, one on each side of the frame and near the upper part thereof, and said longitudinal members extend from one pair of standards to the other.

The rollers c , c' , and c^2 are provided with axial trunnions, which are rotatively mounted in suitable bearings in the posts or standards D', the rollers c c' being mounted between the upper ends of said posts and the roller c^2 being rotatively mounted between the lower ends of the posts at one end of the frame. The roller c^3 constitutes part of a tension device whereby the belt or band C is maintained in proper tension notwithstanding stretching of the belt. The trunnions of said rollers are mounted in the free ends of vertically-swinging arms E E, which are pivoted to clips e, attached to the upper face of the base-board D between the roller and the longitudinal center of said frame. As herein shown, said arms E are made from a single integral rod, the connecting or transverse part E' thereof constituting the pivot for said arms. The free ends of the arms are drawn downwardly toward the base-board by means of two spiral contractile springs E², each attached at one end to one of the arms and at its other end to the base-board. Said springs exert their tension against the belt and maintain the belt taut. The belt-rollers c c' at the upper end of the frame are located with their axes of rotation in the same plane, so that the part of the belt between said rollers is horizontal and, as before stated, is located below the open end of the box and constitutes the support for the cigars in the rack of said box. Said belt is provided throughout its length with a plurality of releasing-apertures c^4 equal in number to that of the longitudinal rows of cigars in the box B. Said openings c^4 are located out of alinement with respect to each other a distance equal to the distance between adjacent longitudinal rows of cigars in the box or the rows of pockets

containing the cigars, so that in each complete turn of the belt each of the openings will pass beneath one of the rows of pockets of the rack. Said openings c^4 are also separated longitudinally of the belt a distance equal to the length of the rows of cigars, so that when one of the openings passes from beneath its associated row of cigars or the pockets containing the same the next adjacent opening will be passed beneath the next row of cigars in position to successively release the cigars therein as the belt is given a step-by-step movement.

The operation is continued until all of the rows of cigars have been released. As the machine shown is designed the contents of one box is released in each complete rotation of the belt. As herein shown the box is designed to hold four rows of cigars, and the belt is therefore provided with four openings c^4 , located laterally out of alinement with each other and each adapted to pass beneath one of the rows of cigars. The belt may be made as wide or narrow as necessary to accommodate the number of rows of cigars contained in the box. The cigars are dropped through said releasing-openings c^4 downwardly into a suitably-shaped chute F, located beneath the upper lap of the releasing-belt to receive the same, and said chute extends outwardly through an opening in the front wall of the box, so as to deliver each cigar as it is released from the box to the outside thereof, as shown in Fig. 1.

One of the rollers c c' c^2 (the roller c' as herein shown) is a driven roller, being provided with a gear-pinion c' , adapted to mesh with gear mechanism of an actuating mechanism, as will hereinafter more fully appear. In order to impart to the belt a positive movement from the driving-roller c' , the belt is herein shown as provided on one margin thereof with a plurality of apertures c^6 , which are adapted to be engaged by teeth c^7 on one end of said roller c' . Said apertures are metal bound and, as herein shown, are formed by inserting eyelets through one margin of the belt.

As before stated, the releasing-belt is adapted to be given a step-by-step movement through the agency of a coin-controlled mechanism, and I may apply for this purpose any form of coin-controlled mechanism which may be adapted to the machine herein shown. As shown in the drawings, G designates a rotative gear-wheel which constitutes part of a coin-controlled mechanism, and said gear-wheel meshes with the gear-pinion C', fixed to the trunnion of the rollers c' . On the shaft g of said gear-wheel G is mounted a ratchet-wheel G', which is adapted for engagement by a pawl g', constructed to prevent retrograde movement of the gear-wheel and therethrough the releasing-belt. The direction of rotation of the gear-wheel remains the same through-

out the operation of the machine, so that the direction of movement of the upper horizontal or active portion of the releasing-belt is uniformly from left to right.

5 It will be observed from the foregoing that the direction of travel of the belt is continuous and that it is never necessary, therefore, to retract or reset the belt at the end of a movement thereof, such as would be necessary if the releasing device, as the belt, were not an endless one. This construction is of considerable importance, as it makes it unnecessary to set the releasing-belt at a certain place when inserting into the case a box of 10 cigars which are to be vended therefrom. When a cigar-box is emptied, therefore, and it becomes necessary to replace the same by a filled box, no attention need be given to the belt, as it will begin its operation at any position thereof. Moreover, the continuous movement of the releasing-belt in one direction makes it unnecessary to provide retracting or resetting mechanism for the belt or other like releasing member, so that the actuating mechanism for the belt may be made very simple and reliable.

The belt is supported midway between the rollers *c c'* by means of a bracket *H*, which consists of a horizontal part *h*, extending 15 transversely beneath the releasing-belt and downturned end portions *h' h'*, which are attached to the longitudinal members or bars *D* of the frame. The horizontal supporting part of said bracket is cut away to provide openings through which cigars released through the belt may fall. In assembling this part of the mechanism the openings in said bracket are located vertically beneath the pockets in the rack of the cigar-box, so that said bracket 20 shall not interfere with the dropping of the cigars through said belt.

The box *B* is supported on the belt-frame described, said box extending between and being supported at its ends upon the transverse members *D* of said frame. As herein shown, said box engages horizontal transversely-arranged guide-bars *I I*, attached to the frame. Said transverse guide-bars *I I* have the form of angle-bars, as shown, and 25 are adapted to receive the lower corners of the box to hold the same from endwise movement on said belt-frame. The vertical portions of said bars are turned inwardly toward each other at the rear ends thereof to afford stops to limit the rearward movement of the box on said frame to insure that the same shall stop with the pockets of the cigar-rack therein vertically over the several releasing-openings of the belt. Coacting with said 30 stops *i* are two spring-pressed latches *J J*, which are pivoted to the end walls of the upper sections of the case, as shown in Fig. 4, and are adapted to hook over the front margins of the end walls. Said latches are placed 35 under the influence of spiral contractile

springs *J'*, each of which is attached at one end to its associated latch between the ends thereof and at its other end to the casing-wall in such manner as to force said box tightly against the tops *i* of the guides *I*. 70 The box is also held from rising by means of spring-arms *K*, which are attached to the rear walls of the box at the sides of the glass portion thereof and extend forwardly and adapted for engagement at their free ends 75 with the top wall of the cigar-box in the manner shown in Fig. 1. The outer ends of said arms are turned upwardly to facilitate the entrance of the box beneath the same in placing a box in said casing. 80

In practice the end wall of the casing may be made removable, so that the belt-frame and superposed cigar-box may be withdrawn from the end of the case. In this event the part of the cigar-chute contained in the casing will be removable with the casing and the part *F'*, located outside the casing, will be made a separate part and attached to the front casing-wall. The belt-frame and cigar-box are shown removed from the casing in Figs. 2 90 and 3.

Certain of the features herein shown may be employed in other relations—as, for instance, the releasing-belt may be associated with a casing of different form and coöperate 95 with a cigar-box of a form different from that shown. Moreover, it is obvious that other changes in the structural details may be made without departing from the spirit of my invention, and I do not wish to be limited to such 100 details, therefore, except as made the subject of specific claims.

I claim as my invention—

1. A vending-machine comprising an endless belt, a portion of which constitutes a support for the articles to be vended, rollers over which said belt is trained, interlocking connections between one of said rollers and the belt, means for imparting to said last-mentioned roller a step-by-step movement continuously in one direction and means for sustaining the articles to be vended in rows parallel with the direction of movement of the belt, said belt being provided with a plurality of release-openings arranged longitudinally of 105 the belt and located laterally out of alinement with each other and each adapted to be passed beneath one of the rows of said articles. 110

2. A vending-machine comprising an endless belt, a portion of which constitutes a support for the articles to be vended, rollers over which said belt is trained, said belt being provided with a plurality of apertures or sockets arranged parallel with the direction of travel of the belt, teeth on one of said rollers adapted 115 to engage said apertures of the belt to drive the same, means for imparting a step-by-step movement to said toothed roller and means for sustaining said articles to be vended in rows parallel with the direction of travel of said 120 125 130

belt, said belt being provided with a plurality of longitudinally-arranged release-openings which are located laterally out of line with respect to each other.

- 5 3. A vending-machine comprising an endless belt, a portion of which constitutes a support for the articles to be vended, rollers over which said belt is trained, said belt being provided with a row of apertures or sockets arranged parallel with the direction of travel of the belt, teeth on one of said rollers adapted to engage said apertures in the belt for driving the belt, means for imparting a step-by-step movement to said toothed roller, a tension device engaging the belt for maintaining the same taut, and means for sustaining the articles to be vended in rows parallel with the direction of movement of said belt, said belt being provided, longitudinally thereof, with 10 a plurality of release-openings arranged laterally out of alinement with respect to each other.
- 15 20

4. A cigar-vending machine comprising a casing, means for supporting in the upper part of the casing a box of cigars, said upper part of the casing being made of sufficient height to permit a box of cigars to be displayed therein with the lid thereof thrown backwardly, the front wall of the box being provided with a swinging or movable door adapted to permit ingress and egress of the box, and said door being made transparent to permit the display through the front wall of the casing of a box of cigars, and means located in the lower part of the casing for releasing one by one the cigars from the box.

In testimony that I claim the foregoing as my invention I affix my signature, in presence of two witnesses, this 16th day of August, A. D. 1902.

FRANK J. BEIER.
